UNITED STATES PATENT OFFICE.

ERNST VON REICHENAU, OF DÜSSELDORF-OBERKASSEL, GERMANY.

ARMORED SHIELD FOR TRAVELING ARTILLERY.

SPECIFICATION forming part of Letters Patent No. 726,988, dated May 5, 1903.

Application filed June 19, 1902. Serial No. 112,339. (No model.)

To all whom it may concern:

Be it known that I, ERNST VON REICHENAU, lieutenant-general, a subject of the German Emperor, residing at 30 Kaiser Wilhelm Ring, 5 Düsseldorf-Oberkassel, Germany, have invented certain new and useful Improvements in Armored Shields for Traveling Artillery, of which the following is a specification.

The armored shields latterly used for artillery such as field-guns, which are intended to protect the gunners against the enemy's fire, are composed of a shield-surface extending from the ground to the axle, of another shield-surface extending from the axle to 15 about the upper edge of the gun, and a third shield-surface projecting up above that point. The part situated below the axle is generally turned up on hinges while traveling, in order not to be in the way; but so long as the gun 20 is not in action the great height of the upper shield-surface forms a considerable impediment, this being particularly the case when traveling, as the shield offers to the wind pressure a considerable resisting-surface, and 25 also it intercepts the view in front of the gunners situated or marching behind the gun. The present invention obviates these several disadvantages by so constructing the part of the shield situated above the axle that it can 30 be reduced to a fraction of its original height either by folding or sliding together the parts thereof. This arrangement can be applied both to armored shields having no opening above the gun, but extended transversely with 35 a closed surface, in which case, for example, the upper part can be turned down upon the gun, as also with such armored shields in which an opening is provided above the gun.

Figures 1 to 6 of the accompanying drawings 40 show, by way of example, a mode of carrying out the said invention in which the shield is provided with an opening above the gun that can be closed by means of flaps *a*. Fig. 1 shows a back view of the shield; Fig. 2, a side view, and Figs. 3 to 6 show details.

The flaps *a* can turn upon hinges *f* and can either be closed, as shown in dotted lines at Fig. 4, or they can be opened by turning them back against the shield-surface *c'*, as shown in 50 full lines at Fig. 4. As shown at Figs. 1 and 2, the lower part *c'* of the armored shield can be turned upon hinges *e'* against the middle part

c, which is a usual arrangement, as above stated. According to the present invention, however, the upper part *c'* can also be turned down upon the hinges *e*. When the shield is provided with an opening, as shown in the drawings, the plates *a* are first turned back against the upper part *c'*, as shown at Fig. 4, and then, as shown at Figs. 5 and 6, the folded parts *a* *c'* are turned down upon the hinges *e*.

In the arrangement shown at Figs. 7 to 11 the shield is provided with lateral wings *d* *d'*, which serve to protect the gunners against projectiles and shells that come from the 65 enemy in a lateral direction. The upper part *d'* of these side wings is divided in the plane of the hinges *e* from the lower part of the side wings *d*, so that it can be turned down, together with the upper part *c'*, in the 70 manner shown at Figs. 10 and 11.

At Figs. 12 and 13 is shown a further arrangement in which also the side wings *d* *d'* can be turned upon hinges *g* against the parts *c* and *c'* of the shield, whereupon the upper 75 parts *c'*, with the folded flaps *a* and also the folded wings *d'*, can be turned down against the middle part of the shield *c*, as shown at Fig. 12 in horizontal section.

In all cases the folded parts of the shield 80 are secured in that position by means of leather straps and buckles secured thereto or in any other suitable manner, so as to prevent them from making a noise when the gun is traveling.

Having now particularly described and ascertained the nature of my said invention and in what manner the same is to be performed, I declare that what I claim is—

1. In an armored shield for traveling artillery, the combination of a part immovably fixed to a gun-carriage, and a part projecting up beyond the gun and movably connected with said relatively stationary part, so that it is adapted to be moved down onto the stationary middle part, substantially as described, for the purpose set forth.

2. In an armored shield for traveling artillery, the combination of a part immovably fixed to a gun-carriage, a part projecting up beyond the gun-carriage and movably connected with the said relatively stationary part, and side wings connected with both said parts, the projecting part being adapted to

be moved with the side wings down onto the stationary part, substantially as described, for the purpose set forth.

3. In an armored shield for traveling artillery, the combination of a middle part immovably fixed to a gun-carriage, a part projecting up beyond the gun-carriage and movably connected with said relatively stationary part, and side wings movably connected with both the said parts, the projecting part and said side wings being adapted to be moved down onto the stationary part, substantially as described, for the purpose set forth.

4. The combination with a field-gun, of an armored shield consisting of a lower part extending beneath the axle, a middle part immovably fixed to the gun-carriage, and a part projecting above the gun-carriage and mov-

ably connected with said middle part, and 20 adapted to be moved downwardly against one face of said stationary middle part, substantially as described, for the purpose set forth.

5. The combination with a field-gun, of an armored shield consisting of a part hinged to the gun-carriage and extending below the axle thereof, a middle part immovably fixed to the carriage, and a part hinged to the upper edge of said middle part and adapted to project above or lie against one face of said 30 middle part, substantially as described, for the purpose set forth.

In testimony whereof I have affixed my signature in presence of two witnesses.

ERNST VON REICHENAU.
